UNITED STATES PATENT OFFICE.

WALTER S. MOSES, OF ANNISQUAM, MASSACHUSETTS.

MACHINE FOR CUTTING FISH.

SPECIFICATION forming part of Letters Patent No. 356,725, dated January 25, 1887.

Application filed July 7, 1885. Serial No. 170,889. (No model.)

To all whom it may concern:

Be it known that I, WALTER S. MOSES, a citizen of the United States, residing at Annisquam, in the county of Essex and State of Massachusetts, have invented a new and useful Improvement in Machines for Cutting Fish, of which the following is a specification.

My improvement consists in machinery for cutting fish into rectangular pieces of equal size, to be piled one on another and so fastened together as to form rectangular blocks for packing solidly into boxes, for the better preservation of the fish and for greater facility in handling the same by dealers, both wholesale and retail.

In the accompanying drawings, making part of this specification, Figure 1 is a perspective view of the fish-cutter. Fig. 2 is an elevation showing the arrangement of the endless belt and the machinery operating it. Fig. 3 is a plan showing the knives and their attachments. Fig. 4 is a plan showing the other parts of the machine, the cutting devices being removed; and Fig. 5 is a vertical section on the line *x x*, Fig. 1.

Like letters in the different figures represent the same parts.

Letter A is the frame of the machine.

H H are sections of an endless table, the ends of which sections are securely fastened to the endless chains B B, which chains are operated by a belt on the pulleys C, whose shaft carries the pinion D, gearing into the wheel E on the shaft F, carrying two pinions, one, G, geared into the rack D of the endless chain B, and the other pinion placed near the other end of said shaft and geared into the rack of another endless chain, like B, placed on the other side of the machine, as shown in Fig. 5.

I I are grooves in the surfaces of the sections forming the endless table, in which run the edges of the rotary knives K K'. L L are also grooves in the surfaces of said sections, in which are placed the free ends of the rods M M. N N are small metallic pins so inserted into the surface of said table that their points rise above its surface half an inch or more.

K K' are rotary knives, each having a separate arbor. The arbors of the smaller knives run in bearings on the brackets O O, which are framed into the beam P, and which beam is framed into the posts Q Q. The arbors of

the larger knives run in bearings on the brackets R R, mortised into the rocking shaft S, having gudgeons with bearings in said posts 55 Q Q. The lever T is also mortised into said rocking shaft S, and throws the larger knives into and out of cutting position, according as it is raised or depressed, and by suitable fastenings holds them firmly in said positions, respectively.

U is a guide fastened to the rocking shaft V, which turns in the bearings W W, fastened to the frame A. The horizontal position of this guide is at right angles to the grooves I I. 65

To the end piece of the frame A are securely fastened slats X X, placed far enough apart to permit the rows of pins N N to pass between them, and made so thin that the points on said pins rise above the tops of said slats. 70

M M are rods serving to remove the cut fish from the pins N N. One end of each of said rods is hinged to the frame A, and the other is held in its corresponding groove, L, sunk in the surface of the endless table, and held in 75 place by the spring Z.

Operation: The surface of the table moves toward the knives in the direction of the arrow shown in the drawings. If a dried fish is to be cut, the larger bones are taken out, the 80 skin removed, and the fish placed lengthwise on the table, skin side down, and held in place by the pins N N. As the fish moves with the surface of the table under the knives K K', said knives are rotated by the motion of the fish 85 and cut it into longitudinal strips, in width equal to the distance between the knives. As the longitudinal strips of fish pass on beyond the knives they are raised off the pins by the rods M M coming between said strips and the 90 surface of the endless table. A quantity of fish having been thus cut into longitudinal strips, the same is returned, by machinery or otherwise, to the front end of the machine, and the guide U is put in place, as shown in the 95 drawings. Then the longitudinal strips of fish are placed with a cut side against the guide U and so pressed down as to be fastened to the surface of the table by the pins N N. Being so placed, the cut sides of the longitudinal strips approach the knives at right angles, and as they pass under the knives are of course 100 cut into rectangular blocks.

When it is desired to cut the fish into blocks

with a length double their width, the large knives are raised out of the cutting position by depressing the lever T.

The grooves in which run the edges of the 5 rotating knives permit the cutting to be done somewhat in the manner in which shears operate, whereby a clean square cut of the fish is effected.

What I claim as my invention, and desire 10 to secure by Letters Patent, is—

1. In a fish-cutting machine, the combination of the endless table consisting of the sections H, provided with the grooves I and pins N, the endless chains B B, carrying said table, 15 and the rotary cutters K K', substantially as described.

2. In a fish-cutting machine, the rotary cutters K, in combination with the sectional table H, provided with the grooves I, to receive the 20 edges of said cutters, and operated by the endless chains B B, substantially as described.

3. In a fish-cutting machine, the combination, with the frame A and the endless sectional table H, of the posts Q Q, the beam P,

framed into said posts, the brackets O O, 25 framed into said beam, the knives K, having bearings in said brackets, the rock-shaft S, having bearings in the posts Q Q, the brackets R R, framed into said shaft, and the knives K, journaled into said brackets, substantially as 30 described, and for the purposes set forth.

4. In a fish-cutting machine, the frame A, in combination with the endless sectional table provided with the grooves L, and the rods M, hinged to said frame and their free ends being 35 held in the grooves L by the springs Z, substantially as described.

5. In a fish-cutting machine, the guide U, hinged to the frame A, in combination with the sectional table and the slats X, fastened at one 40 end to the frame A, substantially as described.

In testimony whereof I have hereunto set my hand in the presence of two witnesses.

WALTER S. MOSES.
